DEVICE FOR PERFORATING THE ENDS OF CIGARS

Martin Caraballo and Joseph G. Zendegui,
Tampa, Fla.

Application April 22, 1935, Serial No. 17,703

3 Claims. (Cl. 131—20)

The present invention relates to improvements in cigar perforating machines and has for an object to provide a device for piercing the ends of cigars whereby the smoke may be readily drawn through the same into the smoker's mouth.

Another object of the invention is to dispense with the necessity of a smoker biting off the end of the cigar preparatory to lighting the same.

10 This is a necessary but uncleanly and disagreeable practice, the tobacco getting into the mouth of the smoker and the grains of the tobacco getting in and about the teeth so that it is sometimes difficult to dislodge the same. The tobacco

15 filler also has an undesirable taste reaction in the mouth.

A further object of the invention is to avoid this undesirable practice and to provide a better draft for the smoke.

20 A still further object of the invention resides in providing a device which will not only perforate the ends or tips of the cigars but will also automatically remove the cut fragments so that they will not find their way into the smoker's mouth.

25 With the foregoing and other objects in view, the invention will be more fully described hereinafter, and will be more particularly pointed out in the claims appended hereto.

30 In the drawings, wherein like symbols refer to like or corresponding parts throughout the several views,

Figure 1 is a side elevation, with parts broken away and parts shown in section, of a device constructed in accordance with the present invention and shown in initial position.

Figure 2 illustrates the same device with the needle projected into the cigar, and

Figure 3 is a longitudinal section showing a modified form of the device.

40 Referring more particularly to the drawings, 5 designates a receptacle maintained in a condition of partial vacuum through the connection of an exhauster or pump, the connection being made at 6, which is a pipe section or nipple upstanding from the screw threaded or other cover 7 of the glass jar or other container or receptacle 5. This cover also carries a pipe neck or nipple 8 connecting with a flexible hose or tube 9 with the vertical branch pipe 10 extending down from a cylinder 11. The axis of the cylinder 11 is preferably horizontal and the cylinder 11 removably carries a head 12 in which is formed a recess or concavity 13 of a shape to receive the tip or closed end of a cigar indicated in dotted lines at 14. At

the base of the concavity 13 is an opening 15 through which slides a hollow needle 16 having a pointed or tapered and sharpened end 17. The needle 16 is affixed as by a set screw 18 or other fastening, in the tubular neck 19 of a plunger 20 mounted to reciprocate in the cylinder 11. Leather or other cups 21 and 22 or other pressure holding devices are carried by opposite end portions of the plunger 20 and expanded outwardly against the interior wall of the cylinder 11. The 10 packing 21 is received upon the reduced neck 19 and against a shoulder 23 of the plunger, the neck 19 being threaded whereby to receive a nut 24 for the purpose of binding the packing against said shoulder 23.

15 The other packing 22 is similarly held against a shoulder 25 by means of a nut 26 threaded upon the plunger rod 27.

20 The plunger 20 is provided with a forwardly cut-away portion 28 in line with the hollow neck 19 and opening through the lower portion of the plunger whereby to communicate with the interior of the pipe section 10. The packing 21 is cut away at 29 in order to match the cut-away portion 28.

25 The plunger rod 27 has pivoted thereto, as indicated at 30, a link 31. The link is pivoted to the upstanding vertical arm 32 of a bell crank lever, fulcrumed at 33 to a support 34. The horizontal arm 35 of the bell crank lever carries an 30 anti-friction roller 36 and is normally held elevated by a coil spring 37 attached to the arm 35 and to a supporting bracket 38 secured by the screws or other fastenings 39 to the support 34.

35 An eccentric 40 is mounted in the support 34 above the roller 36 and the spring 37 maintains the roller 36 up against the eccentric 40. Such eccentric is pivoted at 41 on the support 34 and has attached thereto a crank handle 42 for convenience in rotating the same.

40 In the operation of the device the parts initially assume the position shown in Figure 1 with the crank handle 42 raised and the spring 37 contracted in the act of raising the roller 36 against the eccentric 40, which action holds the needle 45 16 retracted out of the concavity 13. In this position a cigar is centered with its tip or closed end in the concavity 13, which concavity will present the cigar so that the needle will perforate the exact center thereof. Thereupon the crank 50 handle 42 is rotated through a half revolution or down to the position shown in Figure 2, which will cause the high point of the eccentric to descend upon the roller 36, thus distending the spring 37 and causing the bell crank lever to rock 55

about its fulcrum 33. The plunger 20 is forced inwardly into the cylinder 11 and the needle 16 projected through the opening 15 and into the tip end of the cigar. During this time the cigar is held firmly with one hand while the crank 42 is operated by the other hand. Of course the crank will be given one complete turn in the actual operation so as to cause the needle to penetrate the cigar and to be withdrawn therefrom to the initial position shown in Figure 1. The needle will cut a round hole in the tip end of the cigar and by virtue of the hollow character of the needle and its connection with the vacuum receptacle 5 through the tube 9 and its connections, the cuttings or particles cut from the cigar are automatically and quickly drawn out through the needle and into the receptacle 5, thus leaving a clean hole in the cigar free of any loose particles, dust or foreign matter.

20 It is obvious that the operation of the device can be speeded up by connecting the same to an electric motor. This motor may be the same one that operates the exhaust pump. By a suitable tripping device located within the concavity 13 the motor circuit may be closed upon the insertion of a cigar therein. This intermittent motion of the needle may also be produced in other ways.

The hollow needle is made removable so that different diameters can be used to accommodate different sizes of cigars. The block containing the concavity is also removable so as to provide interchangeable blocks with different sized concavities to fit various sizes of cigars. The parts may be made of any material desired. For instance, a successful device utilizes wood for the block 12, iron for the cylinder 11 and brass or bronze for the packing cups 21 and 22. Such packing cups provide a better bearing surface and contribute to the exclusion of outside air which would otherwise rush in to take the place of the vacuum created by the suction pump, thus preventing the full use of said vacuum through the hollow needle.

45 Referring more particularly to Figure 3, there is shown in this case a tapered hollow needle 17^a so as to facilitate the passage of the tobacco which is cut off by the needle. In this case the pipe section 10^a, instead of being connected with the cylinder as in the former case, is carried by the plunger 20^a and reciprocates back and forth therewith. A flexible hose 43 is connected to the pipe section or nipple 10^a and also to the nipple 8 of the receptacle 5, which is not shown in this

figure. This insures that there shall be no loss of vacuum. The flexible hose 43 will preferably be reinforced against collapse. A flexible metal tube such as the ones used in gas stoves, etc. will be useful for the purpose.

5 The device may also take the form of a portable machine shaped somewhat after the fashion of a pistol so that the completed bunches of cigars can be perforated without untying them.

10 It will be obvious that various changes may be made in the construction, combination and arrangement of parts which could be used without departing from the spirit of our invention and we do not mean to limit the invention to such details except as particularly pointed out in the 15 claims.

Having thus described our invention what we claim and desire to secure by Letters Patent of the United States is:—

1. An improved cigar perforating device comprising a cylinder, a plunger therein, a hollow neck extending forwardly from said plunger, said plunger having a cut-away portion back of and communicating with said neck, packing devices on the plunger at opposite sides of said cut-away portion, a hollow cutting tool carried by said neck, and a vacuum connection to said cut-away portion.

2. In a device for perforating the closed tips of cigars, a stationary member having a concavity for receiving the closed tip of the cigar and for holding the cigar in a stationary position with the walls of its tip backed by the walls of said concavity, a hollow perforating needle movable back and forth with respect to said stationary member and having a cutting end portion movable into and out of said concavity whereby to pierce the closed end of the cigar, and means connecting with the hollow interior of the needle for withdrawing the cut portions of the cigar through the hollow portion of the needle.

3. The herein described method for perforating cigar tips, which consists in centering the cigar tip in a stationary position without pressure thereon, backing said cigar tip on all sides, and while said cigar tip is so backed and so stationarily held piercing the tip of the cigar, and removing the cut particles of the cigar in an opposite direction from the piercing action whereby to rapidly withdraw the cut particles as the piercing action progresses.
